UNITED STATES PATENT OFFICE.

JOHN WATTERS, OF NEW YORK, N. Y.

BOX-LOOP.

SPÉCIFICATION forming part of Letters Patent No. 271,170, dated January 23, 1883.

Application filed November 18, 1882. (No model.)

To all whom it may concern:

Be it known that I, JOHN WATTERS, of New York, in the county and State of New York, have invented an Improvement in Box-Loops, 5 of which the following is a specification.

Figure 1 is a plan or top view of my improved box-loop; Fig. 2, a vertical longitudinal section of the same; Fig. 3, a bottom view of a piece of carriage-curtain, to which my box-loop is attached; Fig. 4, a cross-section of the same; Fig. 5, a bottom view of a modification thereof, and Fig. 6 a vertical longitudinal section of said modification.

The object of this invention is to produce 15 for practical use a box-loop for carriages or other purposes, that is made entirely of india-rubber or analogous material—that is to say, where the body of the loop is made without any joint. Leather loops have heretofore been 20 proposed, also metallic loops; but in either case a joint had to be made along the length of the loop, either in form of a seam or as a lap-joint, or otherwise, and where a box-loop was thus formed of folded material with a joint, the 25 joint was apt to open under strain, or otherwise, and to thus destroy the entire value of the box-loop. When india-rubber is used for a box-loop, it can be molded without any joint whatever on a suitable mandrel and in a suitable 30 mold, and can then be attached to the fabric in various ways. One manner of attaching it to the fabric and of attaching to it the usual end buckle is shown in the drawings; and the present invention consists, first, in 35 the employment of a seamless box-loop; and, secondly, in the particular manner, herein described, of fastening the same to the fabric and to the buckle-carrying plate.

In the drawings, the letter A represents the 40 rubber loop, the same being formed of one continuous piece of india-rubber without any joint or seam. This box-loop A is open at the ends in the usual manner. Upon its bottom lies a metallic plate, B, which is turned down and 45 under the box-loop at the ends, as shown in Fig. 2, so as to embrace the back pin of the buckle D, forming a joint on which the buckle can swing. The plate B has two (more or less) 50 prongs, a, formed from it by incisions that cut out the contours of each prong, leaving them,

however, attached at one end, and directly beneath each prong (while the same is still in the plane of the plate B) is cut out of the bottom b of the loop A a piece of a form and size corresponding to the form and size of the prong, 55 producing thereby slots c in the bottom of the loop. Through these slots c the prongs a can be carried down so that they will project vertically below the box-loop A, and these same prongs can then be passed through slits in the 60 curtain or fabric E, and turned under the same, as shown in Fig. 2, thereby fastening the metal plate B to the bottom of the box-loop, and also fastening the entire box-loop to the curtain or the fabric E, and serving also, by the 65 same means, to hold the buckle D properly in place.

The modification which appears in Figs. 5 and 6 consists in substituting for the plate B, that extends throughout the entire length of 70 the loop A, two short plates, B' and B'', each having a downwardly-projecting prong that fastens it to the bottom of the loop and to the curtain; but in this modification the elongated slots c in the bottom of the rubber loop are 75 not needed.

The plate B, as shown in Fig. 2, may be molded onto the bottom of the loop A, if desired, and will not have any projecting part in the way of the necessary sections of the mold 80 in which the rubber is formed, for, while being molded onto the bottom of the rubber loop, the prongs will be flat in the plane of the plate B, and are bent downward through the slot c after the rubber loop has been taken out of the 85 mold. The elastic loop, being rectangular on the outer and also on the inner side in cross-section, as shown in Fig. 4, has equal strength throughout, and is for that reason superior to bent loops, which, when bent, are necessarily 90 weakened at the angles. It also at all times maintains its form, and still yields to pressure and to the bending of the curtain—a property not possessed by loops that might be made of cast metal.

I claim—

1. The rubber box-loop A, provided with means, substantially as described, for attachment to a carriage-curtain or other fabric, for the purpose set forth.

95

100

2. The combination of the box-loop having elongated slots *c c*, with the bottom plate, *B*, having prongs *a a* of a form and size adapting them to enter these slots, all arranged to permit the prongs to be carried down through the bottom plate of the loop and to serve as fasteners for said plate *B* and said loop, substantially as specified.

3. The box-loop *A*, combined with the inner metallic plate having prongs that extend

through the bottom of the loop and through the fabric to which the box-loop is fastened, in combination with the buckle *D*, which is also held in place by the prongs that hold the said inner metallic plate, substantially as specified. 15

JOHN WATTERS.
